UNITED STATES PATENT OFFICE.

CHARLES F. BERGER, OF PELHAM, NEW YORK

COMBINATION CHALK-TROUGH.

1,352,721.

Specification of Letters Patent. Patented Sept. 14, 1920.

Application filed December 31, 1919. Serial No. 348,694.

To all whom it may concern:

Be it known that I, CHARLES F. BERGER, a citizen of the United States, residing at Pelham, in the county of Westchester and State 5 of New York, have invented a new and useful Combination Chalk-Trough, of which the following is a specification.

This invention relates to chalk troughs; and the object of the invention is to provide 10 a device which can be mounted on top of a chalk trough of ordinary construction, and form therewith a chalk trough and holder in which the chalk dust will be separated from the pieces of chalk and erasers, and 15 in which the chalk dust can be cleaned out without disturbing the pieces of chalk and erasers; a further object of my invention is to provide a device of this kind so constructed that the dust can be cleaned out without 20 any projections to interfere with the movement of the hand in cleaning except those absolutely necessary to support the holder of the solid articles; and to provide a construction of such parts that will interfere 25 as little as possible with the movement of the hand in cleaning.

The invention is illustrated in the accompanying drawing, in which—

Figure 1, is a vertical section of a chalk 30 trough combination in accordance with my invention, applied to a blackboard;

Fig. 2, is a front elevation of a portion thereof; and,

Fig. 3, is a plan view of the same portion. 35 In the drawing, like numerals of reference refer to the same parts in each of the views.

In the drawing, the blackboard is indicated with 4, and the chalk trough of ordinary construction with 5, having the ordinary hollow portion 6 to form a receptacle at the lower edge of the blackboard.

In the construction of my invention I provide a number of brackets 7, of a contour to fit within the hollowed part 6 of the trough 5; and these brackets are each provided with a central orifice through which may be passed a screw, as 9 so the brackets can be secured in position.

Each bracket is made of the contour 50 shown in Fig. 1, so the upper part, or chalk and eraser holder can be mounted on the same. As shown, each bracket is provided with shoulders 10, and 11, on which respectively are mounted the rods 12, and 13 adapted to hold the screen 14, through

which the chalk dust may pass, but on which the pieces of chalk and erasers are supported so the pieces of chalk and dust are separated, as will be understood. 60

At the outer edge I mount a strip of molding 15, provided with a groove 16, adapted to embrace the rod 13 and outer edge of the supporting screen 14. This molding strip is provided with a flat side 17, adapted to 65 rest upon a shoulder 18 of each bracket. These parts are so constructed that the side 17 will lie well below the screen 14 that in passing the hand along the open space 19 between the screen and rail, or molding, and 70 the trough 5 there will be nothing to obstruct the passage. The brackets are provided with flattened central portions 21 with rounded sides so the hand will pass over these brackets easily. 75

In operation, the brackets and screen, with the molding, are mounted on top of an ordinary chalk trough. When the dust falls from the blackboard it will pass through the screen 14 to the trough 5. 80 When it is desired to clean out this dust, a brush, or damp rag can be grasped in one hand and passed along the trough to wipe out the dust without disturbing the pieces of chalk, or the erasers on the screen 14, as 85 will be understood. In this operation the open space 19 will provide ready means for the passage of the hand in an unobstructed manner between the two parts. Should it be desired to push the chalk dust past any one 90 of the brackets the rounded, and flattened part 21 will provide ready means for pushing the dust over the bracket without material interference, as will be understood.

It will thus be seen that I have provided 95 a simple and efficient device which may be readily mounted on an ordinary chalk trough so the dust will go into one receptacle while the chalk pieces and erasers will rest in another, and need not be disturbed in cleaning 100 out the chalk dust. Thus, a chalk trough is made out of an ordinary chalk trough common in school rooms.

By bringing the molding strip 15 below the screen 14, the hand can be passed along 105 the trough 5 without interference of any kind except by one of the brackets 7; and these brackets are so constructed that the chalk dust can readily be pushed over the same, if it is not desired to bring the dust 110 out of the trough when the bracket is reached.

I claim:

1. The combination with the chalk trough of a blackboard of a plurality of brackets adapted to rest in said trough, each of said brackets having rounded edges whereby the chalk dust may be pushed over each bracket in either direction, and a screen mounted on said brackets above said trough leaving a space between the screen and the trough whereby a hand may be inserted between the screen and trough, for the purpose set forth. 35
2. The combination with the chalk trough of a blackboard, of a perforated receptacle supported above the trough whereby a space for the insertion of a hand is left between the outer edges of the device and trough, and rounded supports for the receptacle mounted on said trough whereby chalk dust may readily be passed over any of the supports, for the purpose set forth. 40
3. The combination with the chalk trough of a blackboard, of a screen supported above the trough whereby a space for the insertion of a hand is left between the outer edges of the screen and trough, the outer edge of the screen being guarded in a manner whereby a receptacle is formed, and rounded supports for the receptacle mounted on said trough whereby chalk dust may readily be passed over any of the supports, for the purpose set forth. 45
4. The combination with the chalk trough of a blackboard, of a screen supported above the trough whereby a space for the insertion of a hand is left between the outer edges of the screen and trough, a guard mounted on the outer edges of the screen and forming therewith a receptacle, said guard extending below the screen sufficiently to insure protection to the passing hand, and being recessed to receive the outer edge of said screen. 50
5. The combination with the chalk trough of a blackboard, of a plurality of brackets of a contour to fit within the trough of an ordinary chalk trough and secured thereto, said brackets each having two shoulders, a screen mounted on said shoulders on rods which hold said screen in place, and a molding strip recessed to receive the outer rod and outer edge of the screen, and extend below the screen and rod, said brackets each having a shoulder below the outer shoulder on which said screen is mounted, and said molding being mounted on said last-named shoulder. 55

Dated this 29th day of December, 1919. 60
CHARLES F. BERGER. 65
